Assignor to

North, Chase & North, of Philadelphia, Pa.

Letters Patent No. 938. Dated Sept: 1st 1857.

The schedule referred to in these Letters Patent, and making part of the same.

To all whom it may concern:

Be it known that A. G. Wedder, of the City of Troy, County of Rensselaer, and State of New York, have invented or produced a new and original design for stoves, and I do hereby declare that the following is a full and exact description of the same, reference being had to the accompanying drawings, in which

Fig: 1. represents the hearth plate

- " 2. " " side base plate
- " 3. " " back top side plate
- " 4. " " " " front " with door.
- " 5. " " " screen for cylinder
- " 6. " " " top cylinder plate
- " 7. " " " base "
- " 8. " " " door for Sheet Iron Top
- " 9. " " " Top ring
- " 10. " " " " Cover.

What I claim as my invention and desire to secure by Letters Patent, is the design and configuration of the mouldings & ornaments, as herein described, forming an ornamental design for stoves.
